(74) Attorney, Agent, or Firm—Locke Lord Bissell & Liddell, LLP

(57) **CLAIM**

The ornamental design for a lap desk, as shown and described.

DESCRIPTION

FIG. 1 is a perspective view of a lap desk showing my new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof, the left side elevational view being a mirror image thereof.

The broken lines shown in the drawings are included for the purpose of illustrating stitching. The textures shown in the drawings are applied throughout the areas indicated.
